UNITED STATES PATENT OFFICE.

JAMES C. BENNETT, OF DETROIT, MICHIGAN.

BLOWER FOR BOILERS.

1,202,471.

Specification of Letters Patent. Patented Oct. 24, 1916.

Application filed March 6, 1916. Serial No. 82,300.

To all whom it may concern:

Be it known that I, JAMES C. BENNETT, a citizen of the United States of America, residing at Detroit, in the county of Wayne 5 and State of Michigan, have invented certain new and useful Improvements in Blowers for Boilers, of which the following is a specification, reference being had therein to the accompanying drawings.

10 This invention relates to blowers for boilers, and the primary object of my invention is to provide a blower which may be advantageously used in connection with a horizontal return tube boiler or a boiler of the marine type, the blower also being applicable to other types of boilers by a slight modification in the shape and disposition of jet arms forming part of the blower.

Another object of my invention is to provide a steam blower with novel jet arms which may be oscillated whereby the arms will serve all of the tubes of a flue sheet and thoroughly remove soot, incrustations and other matter from the flues or tubes of a 25 boiler.

A further object of my invention is to furnish a blower of the above type with a novel reciprocatory valve which permits of one of the jet arms of the blower being used 30 independent of the other jet arm, thereby conserving steam pressure and allowing the blower to directly and indirectly cleanse tubes or flues of a boiler.

A still further object of my invention is 35 to provide a blower that can be easily and quickly installed, readily operated when occasion requires, and maintained in an operative position within a boiler setting.

The above are a few of the objects attained by the novel construction to be hereinafter described, and reference will now be had to the drawing, wherein there are illustrated the preferred embodiments of my invention, but it is to be understood that 40 the structural elements are susceptible to such variations and modifications as fall within the scope of the appended claims.

In the drawings, Figure 1 is a view of the front end of a horizontal return tube boiler, showing the jet arms of the blower; Fig. 2 is a side elevation of the blower; Fig. 3 is

an enlarged longitudinal sectional view of a portion of the same, illustrating a reciprocatory valve; Fig. 4 is a cross sectional view of the same taken on the line IV—IV of 55 Fig. 3; Fig. 5 is a view of the end of a boiler of the marine type, illustrating a blower installation, and Fig. 6 is a side elevation of one of the blowers.

Referring first to Figs. 1 to 4 inclusive, 1 60 denotes a boiler of the horizontal return tube type having a tube or flue sheet 2, tubes or flues 3, and a boiler setting 4 provided with a door 5 whereby easy access may be had to the space between the flue 65 sheet 2 and the boiler setting. Suitably secured to the inner side of the boiler setting 4 is a bracket 6 coöperating with the boiler setting in supporting the inner end of a steam supply pipe 7. As a matter of good 70 construction, the steam supply pipe 7 enters the boiler setting 4 above the door 5 and extends downwardly to a point in proximity to the crab of the flue sheet 2. The inner end of the supply pipe 7 has a horizontally disposed elbow 8 provided with a stuffing box 9 and a connection 10 for a short pipe 11 extending toward the flue sheet 2. The pipe 11 supports a longitudinally disposed valve body 12 having angle connections 13 and 14 with a by-path 15 establishing communication between the valve body 12 and the angle connection 13. Reciprocable in the valve body 12 is a tubular valve 16 having a central spider 17 connected to 80 the end of a valve rod 18. The rod 18 extends through the pipe 11, the elbow 8 and the stuffing box 9, and through the door 5. On the outer end of the valve rod 18 is a wheel or hand piece 19 which may be removed when the door 5 is to be opened. To prevent the reciprocatory valve 16 from 85 rotating within the valve body 12, said valve has a longitudinal groove or key-way 20, and extending into said groove or key-way is a pin or key 21 carried by the valve body 12. It is through the medium of the valve rod 18 that the valve 16 may be reciprocated in the valve body 12, to close the angle connection 14 and allow the by-path 100 15 to communicate with the valve body or close the by-path 15 and establish commun-

cation between the angle connection 14 and the valve body. It is also through the medium of the rod 18 that the valve body 12 and the pipe 11 may be oscillated or rocked relative to the elbow 8. Connected to the angle connections 13 and 14 of the valve body 12 are irregularly shaped jet arms, each having right angularly disposed portions 22 and 23 and a portion 24 disposed at an obtuse angle to the portion 23. These irregularly shaped arms are in a plane parallel to the flue sheet 2 and the outer ends of said arms are closed by caps 25 and the sides thereof confronting the flue sheet 2 provided with jets or nozzles 26.

The two jet arms shown in Fig. 1 are adapted to serve all of the flues 3 when the blower is oscillated. One arm serves practically half of the flues and the other arm the other half, with each arm shaped to conform to the outline of the marginal flues of the flue sheet. By reference to Fig. 1 it will be noted that the portions 22 and 23 of the left arm are in front of those marginal flues at the lower part of the flue sheet 2 and to the left of the crab, while the portion 24 of the arm is in front of the first vertical row of flues, consequently all of these marginal flues can be thoroughly blown. Assuming that the blower is in the position shown in Fig. 1 and steam is admitted to the elbow 8, the steam passes through the pipe 11 into the valve body 12, through the by-path 15 into the jet arm of the angle connection 13. The steam is blown into the flues 3 on the left hand side of the boiler and the steam may return through the flues at the right hand side of the boiler, thereby blowing the flues direct and indirectly with one arm which is gradually swung clockwise. When the blower arms assume a position the reverse of that shown in Fig. 1, the valve 16 is reciprocated to close the by-path 15 and establish communication between the angle connection 14 and the valve body, whereby steam will be admitted to the right jet arm to directly blow flues on the right hand side of the boiler. With the right jet arm in action the blower is swung counter-clockwise, and when said operations are repeated, the flues 3 are thoroughly cleansed of soot and other foreign matter. With only one of the arms in operation at a time a head of steam may be maintained with sufficient pressure to thoroughly cleanse the flues and during these operations it is only necessary for the fireman or attendant of the boiler to manipulate the wheel or hand piece 19 at the outer side of the door 5. Reference will now be had to Figs. 5 and 6 showing an installation of blowers in connection with a boiler of the marine type. The blowers are very similar to the blower just described with the exception that dif-

ferent brackets 27 are used and arms 28 and 29 of each blower are shaped to serve the flues of the boiler. The arms 28 conform to the outline of the marginal flues of the marine boiler, and the arms 29 are shaped to serve those flues not reached by the arms 28, also an uptake 30 of the boiler. The blowers are alternately operated and the arms 28 and 29 swung in front of the flue sheet, with the arms alternately ejecting steam which enters the flues of the boiler and thoroughly cleanses the same.

I am aware of steam ejecting arms swinging in parallelism with a flue sheet, but such arms have heretofore only served certain of the flues of the boiler, leaving marginal flues unblown, consequently the rated efficiency of a boiler could not be maintained. The arms herein illustrated confront the marginal flues of a boiler and consequently each and every flue is properly blown. By first blowing one side of the boiler and then the other side, the steam is directly and indirectly used and in consequence of such flue treatment, a boiler can be expeditiously and economically cleaned.

What I claim is:—

1. In a blower for boilers, jet arms adapted to be swung in front of a flue sheet and shaped to conform to the outline of the ends of the marginal flues, means adapted for moving said arms, and means adapted for alternately admitting steam to said arms.
2. In a blower for boilers, jet arms adapted to be swung in front of a flue sheet and shaped to conform to the outline of the ends of the marginal flues, and means adapted for swinging said arms and alternately admitting steam thereto.
3. In a blower for boilers, an elbow adapted to receive steam, an oscillatory valve body carried thereby, jet arms in communication with said valve body, and a reciprocating valve in said valve body adapted to alternately admit steam to said jet arms.
4. In a blower for boilers, an elbow adapted to receive steam, an oscillatory valve body carried thereby and provided with a by-path, a jet arm in communication with the by-path of said valve body, a jet arm communicating direct with said valve body, and a reciprocating valve in said valve body adapted to alternately admit steam to said jet arms.
5. In a blower for boilers, an elbow adapted to receive steam, an oscillatory valve body carried thereby, jet arms in communication with said valve body, a reciprocating valve in said valve body adapted to alternately admit steam to said jet arms, and means adapted for oscillating said valve body and reciprocating the valve therein.
6. The combination with a boiler setting, and a boiler having a flue sheet, of an elbow

between the flue sheet of said boiler and the boiler setting adapted to receive steam, an oscillatory valve body supported by said elbow and in communication therewith, jet arms carried by said valve body in front of the flue sheet of said boiler, a valve in said valve body adapted to alternately establish communication between said jet arms and said elbow, and means extending through

said elbow for moving said valve and oscillating said valve body.

In testimony whereof I affix my signature in presence of two witnesses.

JAMES C. BENNETT.
